WILLIAM G. KIRCHHOFF, OF ST. LOUIS, MISSOURI, ASSIGNOR TO THEODORE W. REMMERS, OF ST. LOUIS, MISSOURI.

WEB-FEEDING MECHANISM.

1,108,501.

Specification of Letters Patent. Patented Aug. 25, 1914.

Original application filed September 24, 1912, Serial No. 722,062. Divided and this application filed January 20, 1913. Serial No. 743,180.

To all whom it may concern:

Be it known that I, WILLIAM G. KIRCHHOFF, a citizen of the United States, residing at St. Louis, Missouri, have invented a certain new and useful Improvement in Web-Feeding Mechanisms, of which the following is a full, clear, and exact description, such as will enable others skilled in the art to which it appertains to make and use the same, reference being had to the accompanying drawings, forming part of this specification.

My invention relates broadly to web feeding, and more specifically to a form of mechanism adapted to feed a continuous web from one reeling device to another and to reverse the direction of feed when the web has been unwound from one of the reels.

This application is a divisional application of my co-pending application filed September 24, 1912, Serial #722,062 for tag-addressing machine wherein my device is shown adapted to feed an inking rib.

The principal object of my invention is to provide a simple, strong and positively operating mechanism for feeding a continuous web and for reversing the direction of feed automatically.

A further object of my invention is to provide a feeding mechanism from which the web may be removed and another substituted with but little trouble.

A still further object of my invention is to provide a mechanism for the purpose described, which operates to hold the web taut or fully extended at all times.

Other and further objects of my invention will be hereinafter pointed out or will be obvious upon an understanding of the device.

Figure 1 is a perspective view of my improved feeding mechanism assembled. Fig. 2 is a sectional view of one of the spools.

My invention contemplates the use of a plurality of spools or reels 1 mounted in suitable supports 2. Each spool is formed with a cylindrical barrel portion 4 containing heads 5 closing its ends. Within the barrel portion is pivoted a bell crank lever 6 which has a portion 7 adapted to project through a slot in the side of the barrel. A spring 8 tends to swing the bell crank lever on its pivot so as to project the projection through the slot. Upon the depending arm of the

bell crank lever is pivoted a rod 9 which projects through an opening in one of the headers 5. The pressure of the spring 8 tends to project the rod 9 outwardly and pressure upon the projection 7 tends to swing the bell crank lever on its pivot and retract the rod 9. The mounting for one end of each of the spools comprises the pin 10 having the reduced end portion 11 adapted to fit in a suitable seat in one of the headers 5. The pin 10 is removably mounted in a suitable aperture in the support 2 and is held in place by a spring 12 fitting in the groove 14, or other suitable means. At its other end each of the spools is supported by the drum 15 which is journaled for rotary motion in one of the supports 2. At its outer end the drum 15 carries the ratchet wheel 16, and the drum is also pierced with a channel adapted to receive the projecting end portion of the rod 9, whereby the spool 1 is locked to the drum 15 so as to rotate therewith.

The swing of the lever 6 is of extent such that when the projection 7 is forced inward the outer end of the rod 9 will be retracted below the face of the ratchet wheel 15, and when the projection 7 is forced outward by the spring 8 the end of the rod 9 will project beyond the face of the ratchet wheel 16.

Spring-pressed detent pawls 17 mounted upon the supports 2 coöperate with the ratchet wheels 16 to prevent overthrow. The ribbon or web to be fed 18 is supported on guide rollers 13 and is secured at its ends to the spools 1 in any suitable fashion so that by suitable rotation of the spools 1 it may be wound about their barrel portions 14.

The mechanism for actuating the spools includes a suitable driving member or prime mover 19 and the oscillating link 20 or other suitable mechanism adapted to produce reciprocal movement. In the device illustrated the link 20 is pivoted at 21 so that it will be oscillated by the crank pin 22 carried upon the rotary shaft 19. A reciprocating link 24 is mounted for endwise movement upon the supports 2 adjacent the ratchet wheels 16, and is adapted to be reciprocated longitudinally by the link 20. Pivoted at 25 on the reciprocating link 24 are the dogs 26 which are in the form of bell crank levers having one end adapted to coöperate with the teeth of the ratchet wheels 16 and having the end of the other

arm pivoted at 27 to a shiftable link 28. By virtue of this connection the shiftable link 28 is supported upon the reciprocating link 24, and is adapted to be shifted longitudinally thereof by swinging on the pivots of the dogs 26. A notched block 29 is carried by the shiftable link 28 and a spring-pressed detent 30 carried by the link 24 is adapted to coöperate therewith to hold the shiftable link 28 in adjusted position longitudinally relative to the link 24. Upon the end of the shiftable link 28 is a pawl 31 which is adapted to coöperate with the end of the rod 9 of one of the spools when it is projected beyond the face of the ratchet wheel 16. Upon the other end of the shiftable link 28 is a projection 32 which is adapted to coöperate in a similar fashion with the projecting end of rod 9 on the other spool. When the shiftable link 28 is shifted to the right on the link 24 by virtue of the pivotal connections of the dogs 26, the detent 30 will engage the left hand notch in the block 29, and the left hand dog 26 will be in engagement with the left hand ratchet wheel 16, and upon reciprocation of the link 24 will operate to rotate the left hand ratchet wheel so as to wind the web on the left hand spool. With the link 28 in this position the right hand dog 26 will be out of engagement with the right hand ratchet wheel 16 so as to permit the right hand spool being rotated by the tension on the web to unwind the web from the right hand spool. The pressure of the web wound upon the spools operates to force the projection 7 on the bell crank lever 6 inward so as to hold the rods 9 retracted. When all of the web is unwound from one of the spools this pressure is removed and the spring 8 will swing the lever 6 to force the end of the rod 9 out beyond the face of the ratchet 16. As the ratchet 16 of the cleared spool is rotated the projecting end of the rod 9 will be brought into contact with the end of the pawl 31 and the further rotation of the ratchet wheel will push the shiftable link 28 longitudinally so as to shift the right hand notch of the block 29 into engagement with the pawl 30, the right hand dog 26 into engagement with the right hand ratchet wheel 16, and the left hand dog 26 out of engagement with the left hand ratchet wheel 16. With the parts in this position the direction of the feed of the web will be reversed from left to right, and the web will be reeled from the left hand spool to the right hand spool until unwound from the former when a similar operation of the bell crank lever 6 and rod 9 will be effected so as to shift the shiftable link 28 to the right again by virtue of the pressure of the projecting end of the rod 9 upon the end of the projection 32 of the shiftable link. Thus it will be seen that my feeding

mechanism operates to feed positively the web from one spool to the other, and automatically to reverse the direction of feed of the web when it has been unreeled from one of the spools.

It is obvious that this form of feeding mechanism is not limited to use with an inking ribbon, but that it may be employed in any instance where an intermittent feed for a continuous web is required.

It is obvious also that the arrangement of the spools and their mountings is such that they may be easily removed for the purpose of changing the web, but my device is not limited to the specific forms shown and described.

I am aware that the device shown and described may be altered and modified to suit various conditions and purposes, and I therefore do not intend that my invention should be limited to the specific form and device shown and described, but that it shall be construed to comprehend all forms and modifications employing the essential elements or arrangements of parts thereof.

I claim:

1. A web feeding mechanism comprising a combination of reels, ratchet wheels for rotating said reels, a reciprocating link, a shiftable link, dogs carried by said links and adapted to be shifted by relative movement of the links to coöperate with said ratchet wheels, and means for changing the relative positions of said links to throw said dogs into and out of engagement with their respective ratchet wheels.

2. In a device of the class described in combination, reels adapted to receive a web, movable rods out of operative position in said reels, means operable by a web on said reels for moving said rods, ratchet wheels for driving said reels, a reciprocating member for driving said reels including a dog adapted to engage each ratchet wheel, and members adapted to coöperate with said rods to shift said dogs into and out of engagement with said ratchet wheels when the web is unwound from a reel.

3. A web feeding and reversing mechanism comprising suitable spools for the reception of a web, feeding means coöperating with each spool for rotating the same to wind the web thereon, shifting mechanism for controlling said feeding mechanism, and means carried by said spools and operable by the pressure of the web wound on said spools and adapted to coöperate with said feeding mechanism to operate said shifting mechanism upon the exhaustion of the web from a reel.

4. A web feeding and reversing mechanism comprising in combination suitable spools for the reception of a web, feeding means adapted to intermittently rotate said spools to feed the web, shifting means for

shifting the operation of said feeding means from one to the other of said spools, and means carried by said spools and controlled by the pressure of the web wound upon said spools and adapted to control the operation of said shifting means upon the exhaustion of the web from a reel.

5. A web feeding and reversing mechanism comprising the combination of suitable spools for the reception of the web, means adapted to coöperate selectively with said spools to rotate the same to feed the web, a shifting mechanism adapted to transfer the operation of said feeding means from one to the other of said spools to reverse the direction of feed, a movable member carried by each of said spools and adapted to coöperate with said shifting mechanism to effect the operation of the same, and means operable by the pressure of the web to retain said movable member in inoperative position.

6. A web feeding and reversing mechanism comprising the combination of suitable spools for the reception of the web, a feeding mechanism adapted to coöperate with said spools to feed the web, a reversing mechanism including a shiftable link adapted to shift the operation of said feeding mechanism from one to the other of said spools, a movable member carried by each of said spools and adapted when in operative position to coöperate with said shiftable link to reverse the feeding mechanism, means tending to hold said movable members in operative positions, and means operable by the pressure of the web wound upon said spools and adapted to hold said movable members in inoperative position.

7. A web feeding and reversing mechanism comprising the combination of suitable spools for the reception of the web, a feed-

ing mechanism adapted to coöperate selectively with said spools to feed the web, a reversing mechanism adapted to shift the operation of said feeding means from one to the other of said spools, said reversing mechanism including a detent adapted to frictionally retain said reversing mechanism in selected positions, means carried by each of said spools adapted to shift said reversing mechanism from one to the other of its operative positions, said means including movable members adapted to coöperate with the reversing mechanism, and members operable upon the exhaustion of the web from one of said spools for controlling the operation of said movable members.

8. A web feeding and reversing mechanism comprising the combination of suitable spools for the reception of the web, a feeding mechanism adapted to coöperate selectively with said spools to feed the web, a reversing mechanism adapted to shift the operation of said feeding mechanism from one to the other of said spools, said reversing mechanism including a shiftable link and a detent therefor, said shiftable link being movable with the feeding mechanism, rods carried by each of said spools and adapted to be projected into the path of said link to effect the shifting operation, and means on each spool and operable by the web adapted to hold its associated rod out of the path of said link when a portion of the web is wound on its associated spool.

In testimony whereof I hereunto affix my signature in the presence of two witnesses, this 30th day of December, 1912.

WILLIAM G. KIRCHHOFF.
